ATTORNEY

UNITED STATES PATENT OFFICE

BENGT EMIL BERG, OF CHARLOTTE, NORTH CAROLINA

HOLLOW-METAL PROPELLER

Application filed July 21, 1928. Serial No. 294,443.

This invention relates to improvements in hollow metal propellers adapted primarily for use in aviation service. One object is to provide a propeller of this type that is 5 light in weight and flexible and at the same time of great strength and of maximum durability in use.

With the foregoing and other objects in view the invention consists in the combination and arrangement of parts to be hereinafter fully described, pointed out in the claim and illustrated in the accompanying drawing which forms a part of this application for patent and in which—

15 Fig. 1 is a face view of the propeller, partly in section to afford a better illustration.

Fig. 2 is a side view of Fig. 1.

20 Fig. 3 is a cross section on line 3—3 of Fig. 1.

Fig. 4 is an enlarged view of the propeller rib employed.

Like reference characters denote corresponding parts throughout the several views.

25 The shell of the propeller is made preferably of metal rolled very thin, the shell being of two part formation, the parts being preferably welded together, the hub of the propeller having welded thereto the ends 30 of two ribs that are welded also to the shell sections, the ribs being formed with elongated perforations connected by relatively narrow perforations thus providing a rib construction that is at once light in weight, 35 exceedingly flexible and very strong and durable and that lends great strength to the shell.

The shell of the propeller is of the usual long and narrow shape with the ends 40 rounded and comprises the front plate 1 that is flat and to which the rear plate 2 is secured, the rear plate being of an irregular convex form, the plate 2 rising abruptly from one edge of the plate 1 and being 45 rounded and then tapering off gradually to the opposite edge of said plate, the meeting edges of the plates being preferably welded together.

The hub 3 is welded to the plates 1, 2 and 50 is formed with the central perforation 4 to

receive the propeller shaft. Extending longitudinally and centrally of the propeller shell are the twin ribs 5, the adjacent ends of which are welded to the hub. Each rib is formed of a single piece of material with 55 its wide end 6 welded to the hub, the rib tapering gradually toward its narrow end 7. The ribs are welded to the plate 1 before the plate 2 is welded thereto and spot welded thereto at spaced intervals, the plate 2 being 60 formed with a plurality of perforations to permit it to be spot welded to the rib after it is applied to the plate 1.

Each rib 5 is formed with a plurality of elongated perforations 8 that extend longitudinally of the rib from its larger end, said perforations being successively smaller and narrower and connected together by the slots 9. The perforations 8 reduce the weight of the rib to the minimum and the slots 9 70 provide maximum flexibility.

What is claimed is:—

In a hollow metal propeller, a shell comprising front and rear plates, one of said plates being flat, the other plate being convex and rising abruptly from one lateral edge of said flat plate and then tapering gradually to the opposite lateral edge, said plates having their meeting edges welded together, a hub connecting said plates and 75 being welded thereto, and a pair of twin tapered ribs extending longitudinally of said plates upon opposite sides of said hub and being welded thereto and to said plates, said ribs lying in a common plane and being 80 formed with elongated spaced perforations, said perforations successively becoming narrower as they recede from the larger ends 85 of said ribs, said perforations being connected by narrow slots.

In testimony that I claim the foregoing as my own I have hereto affixed my signature.

BENGT EMIL BERG.
